CLAIM

The ornamental design for a diaper pad fanny pack, as shown and described.

DESCRIPTION

FIG. 1 is a perspective view of a diaper pad fanny pack embodying my new design shown in a closed position;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view of the diaper pad fanny pack, shown in an open position;

FIG. 9 is a rear view thereof;

FIG. 10 is a front view, shown in an open position;

FIG. 11 is a right side view thereof;

FIG. 12 is a left side view thereof;

FIG. 13 is a top view thereof; and,

FIG. 14 is a bottom view thereof.

The broken lines depict portions of the design that form no part of the claimed design.
